STOVE OR FURNACE CONSTRUCTION

Ernest M. Franklin, Kingsport, Tenn., assignor
of one-third to Holiday H. Smith and one-third
to Charles E. Hartgrove, both of Kingsport,
Tenn.

Application March 6, 1944, Serial No. 525,240

3 Claims. (Cl. 110—32)

This invention relates to stoves and furnaces, and the primary object of the invention is to provide a stove or furnace construction whereby proper and complete combustion is had, and whereby gravity feed and even burning of the fuel is effected.

Other objects of the present invention are to provide a stove or furnace construction wherein fuel is fed into the fire box by gravity as the fuel already in the fire box is consumed; wherein there is never a large amount of fuel in the fire box to be coked; wherein combustion is completed in a secondary combustion chamber; wherein grate bars are air cooled internally; wherein only pre-heated air is used to promote combustion; and wherein the fire bed is always of substantially uniform depth.

Other objects and features of the present invention will become apparent from the following description when considered in connection with the accompanying drawings, and the invention consists in the novel form, combination and arrangement of parts hereinafter more fully described, shown in the drawings and claimed.

In the drawings, wherein like reference characters indicate corresponding parts throughout the several views:

Figure 1 is a view, partly in side elevation, and partly broken away and in vertical section, of a stove or furnace constructed in accordance with the present invention.

Figure 2 is a horizontal section taken on line 2—2 of Figure 1.

Figure 3 is a fragmentary horizontal section taken on line 3—3 of Figure 1.

Figure 4 is a fragmentary vertical section taken on line 4—4 of Figure 1.

Figure 5 is an enlarged transverse sectional view of one of the grate bars, taken on the plane of line 5—5 of Figure 1.

Referring in detail to the drawings, 5 indicates a down-draft stack rising from a fire box 6 under which is located an ash pit 7. A grate is provided in the fire box including a plurality of hollow open-ended grate bars 8 whose major forward portions are inclined rearwardly and downwardly, and whose rear end portions are substantially horizontal and arranged upon a wall 9 at the back of the ash pit 7. The bottom of the stack 5 is open and communicates with the fire box.

An opening 10 is provided in the front of the stack 5 near its lower end and directly above the grate 8, and this opening constitutes a fuel inlet leading from a hopper 11 whose inclined bottom wall 12 terminates flush with the bottom of the

opening 10. The hopper 12 has an air-tight lid 13, and it will be seen that the fuel may feed by gravity from the hopper 11 through the opening 10 onto the inclined forward portions of the grate bars. It will also be evident that as the fuel is consumed, it will move downwardly and rearwardly by gravity on the grate to the rear portion thereof and additional fuel will be admitted from the hopper 11 as the consumption of fuel on the grate proceeds.

Provided at the back of the draft stack 5 is an air intake flue 14 having a rear inlet opening 15 at its lower end for the admission of outside air. The flue 14 has a top air outlet 16 constituting an air admission opening for the stack 5 at the top of the latter. Extending along the sides and front of the fire box 6 is a jacket 17 forwardly through which the grate bars extend, and this jacket 17 has rear end portions that extend inwardly to the sides of the flue 14 and communicate with the latter through openings 18 at the bottom of said flue 14. In Figure 1, it will be noted that the rear end portions of the grate bars are spaced below the bottom of flue 14, while the fire box has a front air admission opening 19 so that air may pass from the front of jacket 17 into the fire box directly under the grate. By reason of the wall 9, this air must pass upwardly through the grate to promote combustion of the fuel thereon, after which the products of combustion pass rearwardly between the rear ends of the grate bars and the bottom of flue 14. The ash pit 7 has a clean-out opening 20 closed by a door 21, while the draft stack 5 has a suitable air-tight removable lid 22. Disposed rearwardly of the ash pit 7 is a secondary combustion chamber 23 that is also rearwardly of the grate 8 and that communicates at its upper portion with the fire box above the grate. Any unburned gases passing from the fire box into the chamber 23 will be completely consumed in said chamber 23 before passing from the latter.

It will be noted that the outside air admitted to flue 14 and in jacket 17 will be pre-heated before passing to the fire box, and it will also be seen that outside air is admitted to the fire box both above and below the grate.

As shown clearly in Figure 5, the bars of grate 8 are preferably in the form of elongated hollow tubes 24 having heat-radiating fins 25 projecting inwardly from the walls thereof. Thus, outside air is admitted to the grate bars 24 at the projecting forward ends thereof, and is discharged at the rear ends of the same to promote combustion in the secondary combustion chamber 23.

The hot products of combustion from the fire box and the chamber 23 may be utilized to generate useful heat by passing said products of combustion through a suitable heat exchanger to heat either air or water. As shown, this heat exchanger may be mounted upon the combustion chamber 23 and may be of the type including a casing 26 provided with an air or water inlet 27 at the bottom and an air or water outlet 28 at the top, both communicating with a chamber or space 29 between headers 30 and 31 that are connected by flues 32 through which the products of combustion pass. In other words, the products of combustion pass from the chamber 23 into the header 30, then through tubular flues 32 to header 31. Header 31 may have a suitable smokestack or flue 33 at the top thereof, while the tubular flues 32 may have heat-radiating fins 34. Obviously, the hot products of combustion passing through the tubular flues 32 from header 30 to header 31 will cause the air or water in chamber 29 to be effectively heated for any useful purpose, as such air or water is admitted at 27 and discharged at 28, from casing 26 or the chamber 29 thereof.

In operation, fuel placed in the hopper 11 feeds by gravity through the opening 10 onto the grate 8 within the fire box 6, where combustion is effected by the air admitted through openings 16 and 19 from the flue 14 into stack 5 and from the jacket 17 into the fire box under the grate, respectively. This heated air is supplied in such a manner as to burn the fuel from both top and bottom of the fire bed, and when products of combustion leave the fire box they pass into the secondary combustion chamber 23 where further heated air is available from the internally cooled hollow grate bars, thereby thoroughly completing combustion. Useful heat is obtained from the heat exchanger by passage of the products of combustion therethrough. The opening 15 may be provided with any suitable form of damper for regulating the amount of air admitted for combustion of the fuel on the grate, and as the fuel is consumed, it will move downwardly along the inclined forward portions of the grate bars so that additional fuel will be supplied from hopper 11 to keep a bed of substantially uniform relatively shallow depth on the grate.

The stack 5 facilitates the starting of the fire and removal of any accumulated clinkers, access to said stack above the grate being had by removal of the lid 22. Ashes may be removed from the ash pit 7 when desired by opening the door 21.

It is to be noted that a stove or furnace constructed in accordance with the present invention will be characterized by a minimum of fuel consumption, most efficient utilization of heat generated, and most thorough combustion of fuel with little attention to the fire bed. Other advantages will be apparent to those skilled in the art, and it is believed that the construction and operation will be entirely clear from the foregoing description when considered in connection with the drawings. Minor changes in form and relation of parts may be resorted to, such as fairly fall within the spirit and scope of the invention as claimed.

What I claim as new is:

1. In a stove or furnace construction, a fire box having a grate therein, said grate including grate bars provided with rearwardly and downwardly inclined forward portions and consisting of open-ended tubular members having their for-

ward upper ends projecting at the front of the fire box for the admission of outside air thereto, an ash pit below the grate and fire box, a combustion chamber rearwardly of the ash pit and communicating with the fire box above the grate, said grate bars opening at their rear lower ends into the combustion chamber, a down-draft stack rising from the fire box and having an opening in the rear wall of the upper portion thereof for the admission of outside air, said stack having an opening in the front wall thereof for the inlet of fuel directly above the grate, and a feed hopper for the fuel communicating at its bottom with said fuel inlet opening and adapted to feed the fuel onto the grate as fuel is consumed on the latter.

2. In a stove or furnace construction, a fire box having a grate therein, said grate including grate bars provided with rearwardly and downwardly inclined forward portions and consisting of open-ended tubular members having their forward upper ends projecting at the front of the fire box for the admission of outside air thereto, an ash pit below the grate and fire box, a combustion chamber rearwardly of the ash pit and communicating with the fire box above the grate, said grate bars opening at their rear lower ends into the combustion chamber, a down-draft stack rising from the fire box and having an opening in the rear wall of the upper portion thereof for the admission of outside air, said stack having an opening in the front wall thereof for the inlet of fuel directly above the grate, and a feed hopper for the fuel communicating at its bottom with said fuel inlet opening and adapted to feed the fuel onto the grate as fuel is consumed on the latter, an air intake flue arranged on the rear of and in heat exchange relation to the down-draft stack and communicating at its top with said stack through the air-admission opening of the latter, said flue having an opening for the admission of outside air at the lower portion thereof.

3. In a stove or furnace construction, a fire box having a grate therein, said grate including grate bars provided with rearwardly and downwardly inclined forward portions and consisting of open-ended tubular members having their forward upper ends projecting at the front of the fire box for the admission of outside air thereto, an ash pit below the grate and fire box, a combustion chamber rearwardly of the ash pit and communicating with the fire box above the grate, said grate bars opening at their rear lower ends into the combustion chamber, a down-draft stack rising from the fire box and having an opening in the rear wall of the upper portion thereof for the admission of outside air, said stack having an opening in the front wall thereof for the inlet of fuel directly above the grate, and a feed hopper for the fuel communicating at its bottom with said fuel inlet opening and adapted to feed the fuel onto the grate as fuel is consumed on the latter, an air intake flue arranged on the rear of and in heat exchange relation to the down-draft stack and communicating at its top with said stack through the air admission opening of the latter, said flue having a rear opening for the admission of outside air at the lower portion thereof, and a jacket surrounding the fire box and communicating with said flue, said jacket communicating with the fire box under the grate through an air admission opening of the fire box.

ERNEST M. FRANKLIN.
